Primary Examiner — Robin V Webster(74) *Attorney, Agent, or Firm* — Ohlandt, Greeley, Ruggiero & Perle, LLP**CLAIM**

The ornamental design for the water purification device, as shown and described.

DESCRIPTION

FIG. 1 is a front perspective view of the water purification device according to the present disclosure;

FIG. 2 is a rear perspective view of the water purification device of FIG. 1;

FIG. 3 is a first side view of the water purification device of FIG. 1;

FIG. 4 is a second, opposite view of the water purification device of FIG. 1;

FIG. 5 is a front view of the water purification device of FIG. 1;

FIG. 6 is a rear view of the water purification device of FIG. 1;

FIG. 7 is a top view of the water purification device of FIG. 1; and,

FIG. 8 is a bottom view of the water purification device of FIG. 1.

The broken lines in the drawings illustrating environmental structure or boundaries that form no part of the claimed design.
